[57] CLAIM

The ornamental design for tree protector, as shown and described.

DESCRIPTION

FIG. 1 is a front perspective view of a tree protector, showing my new design;

FIG. 2 is a perspective view in a detached position;

FIG. 3 is a top plan view in the assembled position with the bottom plan view containing no ornamental design;

FIG. 4 is a side view of the tree protector, taken on line 4-4 of FIG. 3;

FIG. 5 is a top plan view in a detached position; and,
FIG. 6 is a side view of the tree protector taken on line 6-6 of FIG. 5.

The broken line showing of a partial tree and grass in FIGS. 1 and 2 is for illustrative purposes only and forms no part of the claimed design.
